UNITED STATES PATENT OFFICE.

DAYTON B. HOLCOMB, OF CHICAGO, ILLINOIS.

ABDOMINAL SUPPORT.

1,259,513.

Specification of Letters Patent. Patented Mar. 19, 1918.

Application filed December 14, 1916. Serial No. 137,063.

To all whom it may concern:

Be it known that I, DAYTON B. HOLCOMB, a citizen of the United States, residing at Chicago, in the county of Cook and State 5 of Illinois, have invented certain new and useful Improvements in Abdominal Supports, of which the following is a description.

My invention belongs to that general class 10 of devices known as abdominal supports, and relates particularly to a viscera support to be used by those afflicted with falling or sagging stomach or viscera, this ailment being known or termed by the medical and 15 osteopathic professions as ptosis. Heretofore physicians of the various schools have applied suspensors, girdles or abdominal bandages for supporting the internal organs, when considered necessary, and in 20 some cases where the patient is troubled with ptosis, it has been possible to afford some relief by the application of such appliances. It has generally, however, been possible to afford relief in such manner 25 where the patient has a large or pendulous abdomen, as a portion of the suspensory or girdle can in that case ordinarily be constructed to underlie the abdomen. In cases where the patients are of slight build or 30 thin, and do not have a protruding or pendulous abdomen, such a band or girdle would generally afford no relief and accomplish no beneficial results, but on the contrary might even be injurious by merely compressing 35 the sagging organs without supporting them. My improved device is particularly adapted and intended for use by patients afflicted with ptosis, hernia, and other ailments, which the same may benefit, and is 40 especially applicable for patients having a straight or non-protruding abdomen, or at least an abdomen where the ordinary girdle, corset or other device would afford no support or relief. The invention has among 45 its objects the production of a device of the kind described that is simple, convenient, efficient, comfortable and satisfactory, that is adapted for male or female patients, and regardless of their physique. It has partic- 50 ularly as an object the production of a support that will extend inwardly the required distance to afford ample support to the various parts or viscera, and prevent the patient from sagging down. The same is 55 adapted for use in cases of certain kinds of ruptures or other troubles. I shall not, how-

ever, endeavor to point out all the uses and advantages of my improved device, as well as the possible variations in the same, to make the same applicable to fit the conditions of the various patients, as the various uses and advantages, as well as the necessary variation of the same will be obvious from the disclosure herein made to those skilled and engaged in the art and professional work in which the need of such devices would be brought to their attention. 65

To this end my invention consists in the novel construction, arrangement and combination of parts herein shown and described, 70 and more particularly pointed out in the claims.

In the drawings, wherein like reference characters indicate like or corresponding parts, 75

Figure 1 is a view in elevation of a portion of a corset with my improved device applied thereto, the inner faces of the pad displayed;

Fig. 2 is a sectional view through the two 80 pads arranged together in operative relation with each other;

Fig. 3 is a perspective view of one of the pad parts;

Fig. 4 is a perspective view of the other 85 part;

Fig. 5 is a front elevation of a pad and girdle particularly designed for male patients;

Fig. 6 is a perspective view of a portion of 90 the patterns employed in making up the pad;

Fig. 7 is a sectional view substantially similar to Fig. 2, enlarged to show the construction;

Fig. 8 is a sectional view through a portion of a human body, illustrating the application of the device; 95

Fig. 9 is a front elevation of a female pelvic, also illustrating the application of 100 the device.

It may be mentioned before describing the device in detail, where the same is intended to be employed by female patients, the same may be fastened directly to the corset, so 105 that it may be applied or removed with the corset. Utilizing the corset permits the doing away with a separate girdle or band for carrying the device and maintaining the same in place. For male patients I prefer to 110 put the device on and form the same as part of a girdle, band, or the equivalent, which

serves substantially as a corset. Obviously, the female patients may use the same kind of a girdle properly fitted to them as shown for the male, if in the opinion of the physician the same seems desirable. In its broadest sense the invention consists of a suitable support having a pad formed therewith and arranged so that when the same is applied to the patient the pad will project inwardly above the upper part of the pubic arch, and forms substantially a shelf or support for the viscera.

Referring to the drawings, I preferably make the support in the form of two pads 1 and 2 of suitable size, shape and material, the exact size and shape depending upon the particular patent for which the same is intended. In the form of the device shown in Fig. 1, one pad is arranged to lap over the other at the inside, while in the form shown in Fig. 5 hereafter described the two pads only abut at their meeting ends or edges. Referring first to the form of the device shown in Figs. 1 to 4 and Fig. 7, the pad part 2 is extended at 3, the extending part 3 being of sufficient thickness to produce enough stiffness so that it is self supporting on the part 2, and does not ordinarily wrinkle or become easily displaced. The device is shown secured to a corset 6, which is of a size to fit the patient, the pads being provided with extending parts 4 and 5 respectively which may be sewed, hooked, laced, or otherwise secured to the corset, this being a matter of preference. Any one of the three methods mentioned is generally satisfactory, the sewed construction being ordinarily preferred for the reasons hereafter given. The application of the same to a girdle or belt, or the equivalent, in lieu of a corset, as shown in Fig. 5, in which 7 represents the girdle, will also be hereafter set forth. Where the pads are made in two parts, as shown, their meeting edges or ends may be detachably secured together by the eyes and hooks 8 and 9, or equivalent means for the purpose. Where the extension 3 is not desired or used, the pad 2 substantially ends at the point marked 10, indicated by the dotted lines in Fig. 4. Where the extension is employed, however, I preferably provide means for securing the outer or free end of the extension 3 to the other pad part, ordinary glove fasteners 11 and 12, or their equivalents, being suitable for the purpose.

The pads shown are preferably formed with the outside substantially straight with the inner face preferably, but not necessarily, bulged or formed as at 14, with the bottom 15 of greater width than the top 16, that is to say the pad is thicker at the bottom than at the top, the same tapering from the inner edge at the bottom to the inner edge of the top, and slightly bulged in the preferred form, as mentioned. This is prob-

ably more clearly shown in Fig. 6, which substantially shows the patterns of the various parts, and 17 being the outer face provided with the ends 18—18, top 19, bottom 20, and the inner face 21. The pad is ordinarily substantially crescent-shaped, as indicated in Figs. 5 and 9, or that is formed to fit the patient, and the same is slightly shorter at the bottom than at the top.

It will be noted by referring to Figs. 2, 3, 4 and 7, that I provide stays 26 at the front of the two pads extending from the top to the bottom. These tend to stiffen the pads and retain them in shape. I also prefer to attach a garter 24, or its equivalent, to each pad, the same being secured to the pads in the preferred construction at the points where the stays are, and preferably about a third of the way up from the bottom. It will be noted by referring to Figs. 1 and 2, 85 that a slight bulge 38' is shown at the inner side of one of the pads. The purpose of this will be more fully explained hereafter. The corset parts are secured together at the front in any of the usual and well known manners.

In the form of the device shown in Fig. 5, in which a girdle 7 is provided, 23 represents a portion of the fasteners, which may be similar to corset fasteners, by which the girdle is secured around and to the body of the wearer. In this case the pad consists of the parts 27 and 28, similar to pad parts 1 and 2, except that they do not overlap, which are secured together by hooks and eyes 29, 100 or equivalent means. The same is also provided with the garters 24 similar to the other construction. While ordinarily the fasteners 8—9 and 29 would maintain the pads in place, assuming that the same is secured to a girdle or corset, I prefer to employ the separate fastening means for the corset and girdle, so that there is practically no pulling strain on the pad parts tending to separate them. In this case the pad parts are secured to the girdle by the parts 30, similar to the parts 4 and 5, in the construction illustrated in Fig. 2. It is, of course, understood that the girdle 7, or its equivalent, is of a size, style and form to most comfortably fit the patient, as well as to provide the support in the desired manner. It may be of any desired material, either elastic or non-elastic. In some cases an elastic material may be found desirable, while in others the elastic material would not be at all suitable or desirable for the patient.

The preceding partially covers in a general way the description of the invention. It may be mentioned, however, that a most satisfactory pad may be constructed as indicated in Fig. 7, in which 32 and 31 may be curled hair or the like, making up the body of the pad, which may be provided with suitable covering 34 of the desired ma- 130

terial. I have heretofore used curled hair, but any suitable material may be employed, this depending entirely upon the requirements of the patient for which the same is intended. The stays 26 may be secured to the inner covering 34 by a strip 35. It may be mentioned that the strips 35 may be extended to the exterior of the pad, as at 36, to provide a place for the attachment of the hooks and eyes 9 and 8, or the equivalent, as for example a lacing, affording a durable construction. In this case the stays and parts 36 will distribute the strain along the pad so that it will not draw at any part. The pad may be and is preferably provided with an outer covering 37, and it may be mentioned that I prefer to make this out of chamois skin or like material, which is soft and durable. Obviously, however, any other material may be provided for the purpose. It will be noted, as previously mentioned, one of the pad parts is provided or formed with a slight bulge 6 to illustrate how the pad may be made to serve as a truss for use in cases of hernia or like trouble. The patient afflicted with hernia often suffers from ptosis, and my pad or supporting device may be constructed to serve both as a viscera support as well as a truss. In this case I provide a part 38 of the desired or necessary size and shape and of suitable material, which may be positioned within the outer covering 37. The part 38 may be made of papier-mâché, wood, cork, metal, or any equivalent suitable for the purpose, and may be satisfactorily secured in place by using a cover 39, and securing this to the inner covering 34. Of course the position of the part 38, and the material employed, together with its size and shape, depends entirely upon the condition of the patient.

The device is ordinarily applied while the patient is lying in a reclining position, so that the viscera to be supported are in normal or substantially normal position. After the patient arises the viscera are then supported by my device. The application, objects and use of the device will be most clearly understood by referring to illustrative Figs. 8 and 9 of the drawings. Fig. 8 represents a vertical section of a portion of a human body, and Fig. 9 a view in elevation of the pelvis. The stomach A, large colon B, and small intestine C, are shown more or less in normal position. They are not, of course, shown in detail, but merely diagrammatically. The abdomen is shown in the dotted lines as it would ordinarily be without my support, and in this case the stomach, colon and intestines, or other parts of the viscera, would be dropped or be lower than shown in Fig. 8, in case of ptosis. In this case P represents the pelvic or pubic arch, and Gimbernat's and Poupart's ligaments extend substantially along

the upper edge of the pelvis, as indicated at L, and the femoral arteries and veins extend between the ligaments and the bone down to the leg, for example, illustrated at the point marked X in Fig. 8, and down as 70 at Y in Fig. 9, dotted lines (not shown with accuracy). My support is constructed of such size and shape that when applied by the patient while in a reclining position, as mentioned, it will lie substantially as shown 75 in Fig. 8, in which S represents the support. It will be noted that the abdomen is forced inwardly and maintained in that position by the device, the lower sides or bottoms of the pad S being above the brim of 80 the pelvis, or pubic arch of the pelvis, the same being a sufficient distance above the bone so as not to crowd Gimbernat's and Poupart's ligaments and the blood-vessels extending over the pubic arch below the ligaments. It projects inwardly, however, the inner lower edge being in some cases a considerable distance inwardly the pubic arch. It will be noted that in this case the viscera will press or bear down on the pad substantially as indicated by the arrows in Fig. 8, 85 and the same carried by the support which is supported by or above the ligaments. The object of the garter previously described and marked G in Fig. 8, which is secured 90 to each pad part, will be obvious by referring to this figure. While the support is maintained in place and prevented from dropping by the corset to which it is attached, or the girdle, as the case may be, 100 the garter positioned up from the bottom tends to throw or tip the lower part of the pad into the abdomen, so that my device forms substantially a shelf on the inner side of the pubic arch, and above the same, 105 thereby properly carrying the viscera.

While ordinarily a two-part pad, as constructed in Fig. 5, is satisfactory, and has proven comfortable and efficient in service, by extending one of the pads over the part 110 indicated at 3 in Fig. 2, and making the co-operating pad part of less thickness, so that they are substantially flush at the outer faces, there is no tendency to pinch or have the flesh protrude at the center of the abdomen or juncture of the pads. In addition, in some cases where the patient has a rupture or hernia, the same may be in such position that the slight gap between the two pads at the center, as might be the case in Fig. 115 5, if the pads were not properly applied, would not be desirable. Where the patient is afflicted with hernia the device may be constructed as shown with the part 38, 120 should the physician prescribe the same. 125 While a one-part pad would be satisfactory in so far as support is concerned, I have found the two-part pad much easier and convenient for the patient to apply, as it is ordinarily somewhat difficult to hook or lace 130

4
at one side, as for example at 4 or 5. Should the patient increase or decrease in weight, it is often necessary or desirable to secure the pads to the corset or girdle in changed positions, or vary the size of the pads. Where the same is applied to the corset or girdle, as shown, it is a comparatively simple thing to do. Where the same is laced, it is, of course, even easier. Where lacings or like fastenings are used, however, there might be some tendency for the patient to make or vary the adjustment, which in some cases might not be desirable.

While my supporting device will support 15 the viscera and afford relief to the patient, it is often desirable that the patient receive osteopathic treatments or the like, as to strengthen the abdominal muscles and walls. Treatments in conjunction with my 20 device may eventually cause the patient to improve until perhaps the support is not required. It may be mentioned that demonstrations of the device and X-ray photographs clearly show that the viscera are 25 fully supported by my device. It also cannot be too strongly emphasized that my device is not merely an abdominal band arranged to contain, press or bind in the viscera, or to serve as a corset or the like, to 30 change the shape of the figure, and should not be confused with such devices, but is to support the viscera and assist and supplement nature.

From the preceding it is obvious that 35 necessarily the device will be modified both as to size, shape and material, to meet the different conditions of various patients; consequently, I do not wish to be understood as limiting myself to the exact form, construction, arrangement or combination of 40 parts herein shown and described, or uses mentioned.

It is however, advisable and necessary to 45 form the pad with the lower thickened portion of a substantial length so that it will extend well across both sides of the central plane of the patient. This is distinguished from a tapered form where the enlarged portion would be centralized somewhat. It 50 is also expedient and necessary to use, in connection with the pad and its supporting

devices, a means which will tend to deflect the thickened lower edge well back in the position, as shown in Fig. 8. Such means has been shown as represented by the straps 55 24, but other "tipping means" may be provided, if desired.

What I claim as new and desire to secure by Letters Patent is:—

1. In a visceral supporting device of the 60 character described, the combination with a member designed to encompass the body of the wearer, of a pad carried by said member of a length to extend across the abdomen of the wearer and having its lower edge part 65 of a substantial length to extend laterally on opposite sides of the wearer and of a greater thickness than the upper edge, and means adjacent the lower edge for tipping the same inwardly when applied to form a ledge to 70 support the viscera in a normal elevated position, substantially as described.

2. In a visceral supporting device of the character described, the combination with a 75 pad supporting element, of a pad formed of 75 two like sections of substantially rectangular formation and having their lower edges thicker than their upper edges, detachable means for uniting the adjacent edges of the pad, and means for deflecting the thickened 80 edges of the pad inward when applied for the purposes specified.

3. In a visceral supporting device of the character described the combination with a 85 carrying element for encompassing the body of the wearer, a divided part of a length sufficient to extend across the forward part of the body on opposite sides of the center, one of said pads having a portion designed 90 to overlap the other, means for securing the pads to the supporting element, means for uniting the edges of the pads, and devices for tipping the lower edges of the pad inward when applied.

In testimony whereof, I have hereunto 95 signed my name in the presence of two subscribing witnesses.

DAYTON B. HOLCOMB.
